UNITED STATES PATENT OFFICE

2,464,521

TELESCOPE RETICLE

Daniel B. McCall, San Antonio, Tex.

Application December 2, 1944, Serial No. 566,318

3 Claims. (Cl. 33—46)

1

This invention relates generally to the class of optics and pertains particularly to improvements in the reticles for telescopes.

A principal object of the present invention is to provide an improved telescope reticle having a light beam slit which presents a hairline of light in the center of the reticle post, to facilitate the sighting of the telescope.

Another object of the invention is to provide an improved telescope reticle having a post provided with a vertical slit or opening through which passes light gathered by the lenses, to form a light beam lying in the vertical center of the lenses, which may be used for accurately sighting the instrument.

Another object of the invention is to provide an improved telescope reticle in which the upper end of the reticle post is provided with a narrow slot which opens through the end of the post and which terminates at the horizontal or cross hair whereby to provide a hairline of light which intersects and is perpendicular to the transverse or horizontal cross hair at the center of the reticle, thereby providing a clearly defined center, by means of which the telescope may be readily sighted or lined up on a distant object even where light conditions are poor and under conditions where it would not be possible to make use of the customary cross hairs or other forms of reticles.

The invention will be best understood from a consideration of the following detailed description taken in connection with the accompanying drawing forming a part of the specification, with the understanding, however, that slight changes or modifications may be made in the illustrated structure so long as such changes or modifications do not depart from the spirit of the invention as defined in the appended claims.

In the drawing:

Figure 1 is a view in elevation of a reticle constructed according to the present invention.

Figure 2 is a section on the line 2—2 of Figure 1.

Figure 3 is a view in elevation of a reticle constructed according to the present invention, but without the lateral cross hair.

Referring now more particularly to the drawing, the reference character "R" generally defines the reticle which, as conventionally constructed, comprises a frame in the form of a flat ring 10, across the center of which is disposed a cross hair 11. This ring 10 facilitates the mounting or installation of the reticle in the

2

telescope structure in the usual well-known manner.

In accordance with the present invention there is provided the reticle post 12, the upper end 5 of which terminates in the plane of the lateral cross hair 11 as shown.

In the longitudinal center of the post 12, is formed a narrow slot 13 of constant width, the upper end of which opens through the top end 10 of the post and has the lateral cross hair 11 disposed thereacross as shown.

The light gathered by the lenses of the telescope passes through the slot or opening 13 to the eye and presents to the eye a narrow sharply 15 defined line of light in place of the customary single cross hairs or the customary solid post with lateral cross hair. Thus the light entering the telescope, in effect, illuminates the centering means so that the telescope can be sighted upon an object under light conditions which would make impossible the sighting of the instrument when using any of the known conventional types of reticles.

20 25 The reticle post constructed in accordance with the present invention furnishes to the eye of the observer a beam of light which passes through the longitudinal center of the telescope so that the eye is automatically drawn to the center 30 and the sighting of the telescope is made to a certain extent, automatic.

From the foregoing it will be readily apparent that the present invention will greatly improve the effectiveness of telescopes or their efficiency, over telescopes using the customary forms of reticle.

While the slotted reticle has been illustrated in association with the lateral cross hair 11, it 40 is to be understood that it is within the scope of the present invention to use the slotted reticle post independently of the lateral cross hair if desired. Accordingly, it is understood that in claiming a slotted reticle post the use of such 45 post with or without the lateral cross hair, is intended.

Figure 3 illustrates the invention without the lateral cross hair 11, shown in Figure 1. Since the other features are the same, the same reference characters are used and, as above stated, the invention contemplates the use of the slotted post 12, either with or without the cross hair.

The reticle post of the present invention, being slotted, permits the observer, in sighting, to elevate the top end of the post and still see the

object through the slot. This is impossible with the solid reticle post at present in use.

I claim:

1. In a telescope reticle, a flat ring adapted to be mounted in a telescope, a vertical reticle post within and on the radius of the ring and terminating at its free end in the radial center of the ring, and a slot of constant width throughout its length formed through the post and extending longitudinally thereof, the slot extending through the free end of the post and lying in line with the radial center of the ring. 10

2. In a telescope reticle, a flat ring adapted to be mounted in a telescope, a reticle post within the ring and terminating at its free end in the radial center of the ring, a slot formed through the post and longitudinally thereof, the slot extending through the free end of the post and lying in line with the radial center of the ring, and a lateral radial cross hair intersecting said slot. 20

3. In a telescope reticle, a flat ring adapted to be mounted in a telescope, a reticle post within

the ring and terminating at its free end in the radial center of the ring, a slot formed through the post and longitudinally thereof, the slot extending through the free end of the post and lying in line with the radial center of the ring, and a lateral radial cross hair extending across and over the top of the free end of the reticle post and over the end of the slot. 15
